The ornamental design for a holder for rectangular container, as shown and described.

DESCRIPTION

FIG. 1 is a top corner isometric view of a holder for rectangular container showing my new design;

FIG. 2 is a side elevational view thereof, all other side elevational views being identical;

FIG. 3 is a top plan view thereof; and,

FIG. 4 is a bottom plan view thereof.

The broken lines are for illustrative purposes only and form no part of the claimed design.
